UNITED STATES PATENT OFFICE.

HARRY H. ALFREY, OF EL RENO, OKLAHOMA.

APPARATUS FOR REMOVING GRAIN DOORS.

Application filed January 19, 1922. Serial No. 530,313.

To all whom it may concern:

Be it known that I, HARRY H. ALFREY, a citizen of the United States, residing at El Reno, in the county of Canadian and State 5 of Oklahoma, have invented certain new and useful Improvements in Apparatus for Removing Grain Doors, of which the following is a specification.

My invention relates to apparatus for removing grain doors from box cars, and the principal object of the invention is to provide a simple, inexpensive and economical apparatus for accomplishing this operation, preferably by a single movement of an implement specially designed for this purpose, which is inserted under the grain door or a section thereof and is raised to exert an upward pull on the door, or section, and simultaneously therewith an inward thrust 20 which serves to back out or loosen the nails attaching the grain door to the door posts of the car.

The invention consists in the new and improved arrangements, devices and constructions to be hereinafter described and claimed, for carrying out the above stated object and such other incidental objects as will be mentioned in the following description of the preferred embodiment of the invention disclosed in the accompanying drawing.

In the drawing,

Fig. 1 is a side elevation of the apparatus shown as applied to the upper portion 35 or section of a grain door, the door and box structure of the car being shown in section.

Fig. 2 is a side view, on a larger scale, of the implement employed for removing the door.

Fig. 3 is a view, in perspective, of the hook element of this implement, and

Fig. 4 is a similar view of the part of the implement which exerts the inward thrust.

In the drawing, 10 designates the flooring 45 of a box car, 11 the side wall structure formed with the usual door opening, and 12 one of the door posts. The car is shown as provided with a grain door of common construction. The apparatus of my invention 50 might, however, be used for the removal of grain doors otherwise constructed. The door, as shown, consists of three outside sections 13, 14, 15 which are fastened to the door post by nails 16 and two lining sections 17 and 18 which break joints with the outer sections.

The implement for removing the grain door consists of a hook or claw 19 having a shank 20 formed at its upper end with an eye 21 and at its lower end with a foot 22 60 preferably wedge-shaped so as to provide a sharp, forward edge 23 and a sloping upper surface 24. The surface 24 is preferably corrugated, ribbed or roughened as indicated at 25.

Any suitable apparatus may be provided for elevating the hook 19. I have shown the hook as suspended by its eye 21 on the end of a cable 26 which extends over a sheave 27 and is wound on a drum 28 loose on a 70 shaft 29 but adapted to be engaged therewith by a clutch 30, the handle of which is shown at 31. The shaft is shown as provided with a gear wheel 32 meshed with a pinion 33 on the driven shaft of motor 34. 75 The upper end of the hook 19 is formed with a projection 35 extending upwardly and backwardly from the shank 20 of the hook. Pivoted to the upper end of the oblique projection 35 is a strut 36, the other end of 80 which is pivoted to a member adapted to exert an inward thrust against the grain door when the hook is elevated. This member is shown as consisting of a pair of angle shaped elements 37, 37 held in spaced 85 relation by tubular spacers 38 and bolts 39 extending through the outwardly projecting flanges of the angle elements and through said spacers, the connections between the strut and the members between 90 which it is placed being made by pivot pins or bolts 40.

Operation: The grain door may be removed from the car as a unit by forcing the wedge-shaped foot between the lower edge 95 of the door and the flooring 10 of the car, and then lifting the hook by operation of the winding drum 28. Preferably, however, the door is removed in sections, Fig. 1, showing the application of the implement to the 100 upper section of the door. That is, the wedge-shaped foot is driven in between the upper section and the intermediate section of the door near one end of the door and the hook then raised to remove this section and 105 upper liner 17. It will be observed that the cable 26 is attached to the hook at a point which is nearer the face of the door than is the pivotal point between the strut and the hook. As a result, an upward pull on the 110 hook causes the member 37, 37 to exert an inward thrust against the grain door (op-

erating to loosen the nails 16 and cause them to back out of the door posts) without exerting any force tending to pull the foot out of engagement with the door. This inward thrust takes place simultaneously with the upward pull against the door section. The compound movement thus produced is very effective in removing the grain door boards from the car without breaking them; an important object of my invention being to remove the lumber constituting the grain door without damage so that the grain door boards or sections may be used repeatedly. The upper face 24 of the foot portion of the hook is sloped so that in the oblique position which the hook assumes when exerting a pull on the door, the face 24 will be substantially at right angles to the face of the door. This relation of the parts maintains the proper position of the foot against the under edge of the door or door section. However, to insure this engagement the upper surface of the foot is preferably corrugated or roughened as shown.

25 The intermediate section of the door may be next removed by inserting the foot of the hook between the outer sections 14 and 15. Finally, the hook is inserted under the lower section 15 and the operation repeated.

30 I claim:

1. In apparatus for removing grain doors from railway cars, the combination of a hook or claw comprising a shank and a foot adapted to extend under a grain door or grain door section, and means attached to the shank for elevating the hook.

2. In apparatus for removing grain doors from railway cars, the combination of a hook or claw comprising a shank and a foot adapted to extend under a grain door or grain door section, means attached to the shank for elevating the hook, and means associated with the hook for exerting an inward thrust against the door simultaneously with the upward pull.

3. In apparatus for removing grain doors from railway cars, the combination of a hook or claw comprising a shank and a wedge-shaped foot having a sharp edge adapted to extend under a grain door or grain door section, and means attached to the shank for elevating the hook.

4. In apparatus for removing grain doors from railway cars, the combination of a hook or claw comprising a shank and a wedge-shaped foot having a roughened upper surface and a sharp edge adapted to extend under a grain door or grain door section, and means attached to the shank for elevating the hook.

5. In apparatus for removing grain doors from railway cars, the combination of a hook the lower end of which is adapted to engage a grain door or door section provided with a strut at its upper end having

means adapted to bear against the door, and means for raising the hook to exert an upward pull and an inward thrust against the door.

6. In apparatus for removing grain doors from railway cars, the combination of a hook, the lower end of which is adapted to engage a grain door or door section, a member adapted to bear against the door above said place of engagement, a strut pivoted to the upper end of the hook and to said member, and means for raising the hook to exert an upward pull and an inward thrust against the door.

7. In apparatus for removing grain doors from railway cars, the combination of a hook the lower end of which is adapted to engage a grain door or door section, a strut associated with the upper end of the hook and provided with means for bearing against the door, and means for raising the hook attached to said hook at a point which is nearer the door than is the outer end of the strut.

8. In apparatus for removing grain doors from railway cars, the combination of a hook having a foot adapted to extend under a grain door or door section, a strut associated with the upper end of the hook provided with means for bearing against the door, and means for raising the hook which is attached to the hook nearer the door than is the outer end of the strut, the upper face of said foot being at substantially right angles to the face of the door when the hook is in operative position.

9. In apparatus for removing grain doors from railway cars, the combination of a hook, the lower end of which is adapted to engage a grain door or door section, a member adapted to bear against the door above the place engaged by the hook, a strut pivoted to said member and to said hook, and means for raising the hook which is attached to said hook at a point nearer the door than is the pivotal connection between the strut and hook.

10. In apparatus for removing grain doors from railway cars, the combination of a hook having a foot adapted to extend under a grain door or door section, a member to bear against the door at a point above said foot, a strut pivoted to said member and to said hook, and means for raising the hook which is attached to the hook at a point nearer the door than is the pivotal connection between the strut and hook, the upper face of the foot being at substantially right angles to the face of the door when the hook is in operative position.

11. In apparatus for removing grain doors from railway cars, the combination of a hook member having a shank, a wedge-shaped foot the upper surface of which stands at an obtuse angle to the shank, a

projection extending outwardly and upwardly from the upper end of the shank, a member to bear against the door, a strut pivoted to said member and to the upper end of said projection, and means for raising the hook which is attached to the hook below and inwardly of the pivotal connection between the strut and said projection.

12. In apparatus for removing grain doors from railway cars, the combination of a hook member having a shank, a wedge-shaped foot the upper surface of which stands at an obtuse angle to the shank, a

wardly from the upper end of the shank, a member to bear against the door, a strut pivoted to said member and to the upper end of said projection, and means for raising the hook which is attached to the hook below and inwardly of the pivotal connection between the strut and said projection, the upper face of said foot being inclined so that, when the hook is in operative position it stands at substantially right angles to the face of the door and being roughened, for the purpose described.

HARRY H. ALFREY.
